HUGH G. ROSS, OF WILKINSBURG, PENNSYLVANIA, ASSIGNOR TO WESTINGHOUSE ELECTRIC & MANUFACTURING COMPANY, A CORPORATION OF PENNSYLVANIA

TRANSFORMER CORE

Application filed February 28, 1931. Serial No. 518,115.

My invention relates to transformer cores and has particular relation to core constructions for transformers requiring high reactance.

5 High reactance is frequently desirable or necessary in a transformer to limit, to a safe value, the current supplied by the secondary winding, and, in cases in which a transformer is used to connect a constant-potential source 10 of power to a load the impedance of which may vary through a wide range, high-reactance characteristics may be utilized to maintain a substantially constant output or load current.

15 As is known, the reactance of a transformer increases with the leakage magnetic flux. The reactance may, therefore, be controlled or adjusted to different values if some means is provided for changing the reluctance of the 20 magnetic leakage path in the core structure of the transformer. My invention is primarily directed to a core construction for transformers wherein adjustment of the reactance thereof may be made after the structure is assembled.

25 Generally stated, it is an object of my invention to provide, in a transformer, a core structure so disposed that its parts may be readily adjusted to different relative positions to provide the different desired reactances for the transformer.

Another object of my invention is to provide, in a high-reactance transformer, a core 30 of such construction that individual adjustment of each transformer unit is possible, during manufacture, to allow the meeting of varying reactance requirements without departure from a uniform or standard design 35 of the core parts.

In practicing my invention, I provide a 40 transformer core comprising two separate and relatively shiftable members so formed that their faces on opposite sides of the air 45 gap in the magnetic leakage path are disposed at an angle with respect to the core axis. Relative shifting of the two members thus effects a change in length of the leakage gap without changing the magnetic properties of 50 the other portions of the core and produces

the desired changes in the transformer reactance.

The invention, both as to its organization and its method of operation, together with additional objects and advantages thereof, 55 will best be understood from the following description of specific embodiments, when read in connection with the accompanying drawing, in which:

Figure 1 is a perspective view of a transformer constructed in accordance with my invention;

Fig. 2 is a diagrammatic view of the core of the transformer of Fig. 1;

Figs. 3 and 4 are similar views of transformer cores of other types disposed in accordance with my invention;

Fig. 5 is a circuit diagram illustrating one typical application in which the transformer of my invention is used, and

Fig. 6 is a diagram of curves illustrating the adjustable characteristics afforded by my invention when embodied in a transformer used in the system shown in Fig. 5.

Referring to the drawing, particularly Fig. 1 thereof, the transformer illustrated comprises a magnetic core structure comprising two separate members 10 and 11. The primary and secondary windings 12 and 13, respectively, surround the member 11 and are spaced apart by the central or magnetic leakage leg 14 of the E-shaped core member 10.

All of the core parts are built up of sheets or laminations, as indicated in Fig. 1, to prevent excessive eddy currents. Suitable means for holding the laminations together may be provided in the form of rivets, shown at 15, or their equivalent.

The diagrammatic representation of Fig. 2 supplements the perspective drawing of Fig. 1, just described, and shows more clearly the core construction. Similar reference numerals are used in both figures.

To permit a simple and ready adjustment in the length of the magnetic leakage gap 16, the faces of the core members on opposite sides of the gap between the end of the central leg 14 of member 10 and core member 11, are formed at an angle of some such value

as is indicated in the drawing with respect to the core axis, and provision is made for shifting the core member 11 in an axial direction along member 10. Suitable clamping means, shown at 17, are provided for holding the two core members firmly in place in their adjusted positions, and may be loosened to permit relative movement of the members. It will be seen that a shift of core member 11 to the left shortens the gap 16, while a shift to the right lengthens the gap.

Fig. 3 illustrates another embodiment of my invention which, as will be seen, provides for a reactance adjustment comparable to that of Figs. 1 and 2. Primary and secondary windings 12 and 13 surround the symmetrically formed winding member 18 which cooperates with the two similar E-shaped core members 19 in the manner illustrated.

The two air gaps 20 in the magnetic leakage circuits may be adjusted in length by shifting the position of core member 18 with respect to that of the cooperating members 19 to effect a desired change in the transformer reactance.

In Fig. 4, my invention is shown applied to a core structure adapted to carry, on the slidably disposed bar member 21, one primary winding 22 and two secondary windings 23. Cooperating with bar member 21 are similar core members 24. The two sets of air gaps 25 and 26 may be adjusted in length by shifting the position of member 21, in the manner already explained.

One of the applications to which a transformer of the type just described is particularly suited is for the energization of neon electric signs. In this, as in other applications, it is desirable that the transformer used shall be capable of satisfactory performance over a wide range of different operating conditions, and the core construction of my invention makes possible such desired broad adaptability. Fig. 5 illustrates a transformer, shown generally at 27, supplied with power from a constant-potential source 28 and disposed to energize either of two neon-filled glass tubes 29 and 30. These tubes may be considered as being of substantially similar design but of different lengths as indicated by dimensions A and B.

A transformer of the ordinary constant-potential design, when used in system of this application, would supply a relatively high current to the short length of neon tube 29 and a relatively low current to the much longer length of tube 30, since the resistance is substantially a direct function of the tube length. A transformer of high leakage reactance, such as is described and illustrated in the drawing overcomes this objection, since its secondary-current characteristic may be made substantially flat, as indicated by curve 31 of Fig. 5. It will be evident, from examination of this curve, that the current supplied

to short neon tube A is only slightly greater than the current supplied to the longer tube B, the difference being of such small magnitude that the neon-tube operation is satisfactory in both cases.

Through the provision of an adjustable feature in the magnetic leakage member of a high-reactance transformer, it is possible to shift the position of the secondary-current characteristic by correspondingly changing the length of the leakage air gap. Again, in neon-tube applications, this feature is particularly valuable, since it is frequently desirable to operate the tubes at current values above or below some intermediate value to obtain, respectively, high brilliancy at the expense of tube electrode life or long life for the electrodes at a correspondingly lower brilliancy.

Assuming that the transformer of Fig. 1 is connected in the circuit of Fig. 4, as at 27, the secondary-current characteristic 31 of Fig. 5 would obtain for some intermediate value of air gap 16. Shifting the core member 11 to the left effects a shortening of gap 16, and shifts the secondary-current characteristic to a lower value, such as is indicated at 32 in Fig. 5. Likewise, a shift of core member 11 to the right correspondingly lengthens the gap 16 and raises the secondary-current characteristic of the transformer to some higher value, as indicated at 33.

It will, therefore, be seen that a transformer embodying a core structure of the type just described not only has a substantially flat secondary-current characteristic but likewise, through the provision of reactance adjustment, is capable of shifting this secondary characteristic to meet the needs of a variety of different applications and, in so doing, makes use of core parts of simple, inexpensive and easily manufactured design.

Although I have shown and described certain specific embodiments of my invention, I am fully aware that many modifications thereof are possible. My invention, therefore, is not to be restricted except insofar as is necessitated by the prior art and by the spirit of the appended claims.

I claim as my invention:

1. A magnetic core structure, comprising cooperating members disposed and shaped to provide a plurality of magnetic paths including at least one air gap between opposing faces of said members, said core members being so supported as to maintain them in engagement at a plurality of contacting surfaces and permit an axial sliding movement of one member along the other member, the faces of the core members on opposite sides of the air gaps being substantially parallel and disposed at an angle with respect to the axis of movement so that the length of air gap is dependent upon the relative positions of the said cooperating core members.

2. In a magnetic core structure comprising two cooperating members having a plurality of surfaces thereof in engagement and shaped to provide a plurality of magnetic paths one or more of which includes an air gap between opposing surfaces of said two members, the faces of the core members on opposite sides of said air gap being parallel to each other and disposed at an angle with respect to the core-member axes, the position of one member relative to that of the other being slidably adjustable along said engaging surfaces to effect a change in the air-gap length. 70
3. In a transformer, a magnetic core comprising, in combination, an E-shaped member and a bar member cooperating therewith to bridge the two outside projecting legs and to form an air gap at the end of the central leg thereof, the faces of the core members on opposite sides of said gap being parallel to each other and disposed at an angle with respect to the bar member axis, and provision for shifting, in an axial direction, the position of the bar member relative to that of the E member to effect a change in the air-gap length without affecting the magnetic properties of the outside core legs. 80
4. A transformer comprising a magnetic core having an E shaped member and a cooperating bar member disposed to bridge the ends of the projecting legs of the E shaped member, a primary winding and a secondard winding disposed about said bar member on the respective lengths thereof included between the central leg and each of the two outside legs of the E member, said core members being so formed that a gap is left between the bar member and the end of the central core leg, the core member faces at said gap being parallel with each other and disposed at an angle with respect to the bar member axis, one of said core members being movable in an axial direction with respect to the other core member to thereby adjust the length of said gap. 90
5. In a transformer, a magnetic core comprising, in combination, a winding-carrying bar member and a plurality of E shaped members cooperating therewith, said core members being so shaped and disposed that the two outside projecting legs of each of the E members are bridged by the said bar member and air gaps are provided between the bar members and the ends of the intermediate projecting legs of said E members, the faces of the core members on opposite sides of said gaps being parallel to each other and disposed at an angle with respect to the bar member axis, said core members being so disposed as to provide for adjusting their relative positions by a sliding movement therebetween to effect a change in the several air-gap lengths. 100
6. A transformer comprising a magnetic core having a winding-carrying bar member and one or more E shaped members cooperating therewith, said core members being so shaped and disposed that the two outside projecting legs of each E member are bridged by the said bar member and an air gap is formed between it and the end of the central projecting leg of each E member, the faces of said gap being parallel with each other and disposed at an angle with respect to the bar member axis, said bar member being so disposed as to be movable in an axial direction relative to the E members to effect a change in the air-gap lengths without affecting the magnetic characteristics of the outside core legs. 110
7. In a transformer, a magnetic core comprising, in combination, a winding-carrying bar member and one or more outer core members cooperating therewith, each of said outer members comprising a common longitudinal section and four legs projecting perpendicularly from one side thereof in spaced relation along the said section length, said core members being so shaped and disposed that the ends of the projecting legs of the outer member are bridged by the said bar member and air gaps are formed between it and the end of each of the two intermediate projecting legs, the faces of each of said air gaps being parallel with each other and disposed at an angle with respect to the bar member axis, and provision for shifting in an axial direction the position of the bar member relative to that of the cooperating outer members to effect a change in the lengths of the several air gaps. 120
8. In a transformer, a magnetic core comprising, in combination, a winding-carrying bar member and one or more outer core members cooperating therewith, each of said outer members comprising a common longitudinal section and a plurality of legs projecting perpendicularly from one side thereof in spaced relation along the said section length, said bar member and the outer member projecting legs being so shaped and disposed that the ends of two or more of said legs are bridged by the bar member, and air gaps are formed between it and the ends of each of the remaining legs, the faces of each of said air gaps being parallel with each other and disposed at an angle with respect to the bar-member axis, and provision for shifting in an axial direction the position of the bar member relative to that of the cooperating outer members to effect a change in the lengths of the several air gaps. 130

In testimony whereof, I have hereunto subscribed my name this 17th day of February, 1931. 125

HUGH G. ROSS.
